UNITED STATES PATENT OFFICE.

OTTO BASTEN, OF RUTHERFORD, NEW JERSEY.

DESIGN FOR A TIRE.

Application filed January 15, 1924. Serial No. 8,321. Term of patent 7 years.

To all whom it may concern:

Be it known that I, OTTO BASTEN, a citizen of the United States, and a resident of Rutherford, in the county of Bergen and State of New Jersey, have invented a new, original, and ornamental Design for Tires, of which the following is a specification, reference being had to the accompanying drawing, forming part thereof.

I claim:

The ornamental design for a tire, as shown.

OTTO BASTEN.
